[57] CLAIM

The ornamental design for a “portable light and charging base,” as shown and described.

DESCRIPTION

FIG. 1 is a side perspective of a portable light and charging base of this invention.

FIG. 2 is a front elevational view of the light and charging base of FIG. 1.

FIG. 3 is a rear elevational view of the light and charging base of FIG. 1.

FIG. 4 is a view from the right side of FIG. 2.

FIG. 5 is a view similar to FIG. 4, from the opposite side thereof; and,

FIG. 6 is a top plan view of a portable light and charging base of FIG. 1.
